UNITED STATES PATENT OFFICE

ERIK GRANSTEDT, OF STOCKHOLM, SWEDEN, ASSIGNOR TO AKTIEBOLAGET FORMATOR, OF STOCKHOLM, SWEDEN, A JOINT-STOCK COMPANY OF SWEDEN

MACHINE FOR THE SEPARATION AND FORMATION OF THE FILLER OF CIGAR BUNCHES

Application filed March 8, 1928, Serial No. 260,112, and in Germany March 17, 1927.

In the manufacture of cigar bunches, where the filler consists of whole tobacco leaves or large leaf parts, it is known to be of great importance that these leaves or leaf parts are arranged in the longitudinal direction of the cigar instead of lying transversely thereto, and that the leaves constituting the filler are not unnecessarily broken or cut during the work, but obtain the greatest length which is theoretically possible to obtain with respect to the shape of the cigar.

The present invention relates to a method for obtaining this purpose, the invention consisting substantially in that a tobacco string is produced for each bunch, which string is considerably longer than the bunch, and from which the filler required for the bunch is stamped out, this being effected in known manner so that the filler will be practically parallel to the longitudinal direction of the string.

The string is produced directly out of a suitable quantity or portion of tobacco leaves or leaf parts which are brought into a position where they are parallel to each other, if they do not previously occupy such a position. This leaf bundle is then pressed together in the transversal direction, in order to shape the string to the desired width. The tobacco portion should obviously be adapted so that the part of the string from which the bunch filler is stamped out will be of uniform thickness. Consequently, the leaves are thus permitted in the course of pressing to remain in that position, counted in the longitudinal direction, which they have occupied on having been arranged in parallel to one another. It is evident that the ends of the string will thus be uneven, in that the leaves project at the ends by a varying amount, according as the leaves are of a different length or occupy different positions. After the stamping of the bunch

in are cut to the least possible extent. These leaves or leaf parts are also comparatively long on account of the great length of the string in relation to the bunch or the leaves, and in certain cases such levers or leaf parts will still be whole, for which reason they are used, according to the invention, together with new leaves to form a new leaf bundle for the leaf string.

Of course, the string should not be made longer than required to attain the desired result. If the string is made so long that the waste will be very large, the method will of course be uneconomical. The portion thereof which is of uniform thickness should, however, be at least as long as the cigar, whereas the length of the outwardly tapering end portions of the string will be dependent on the length of the leaves.

It should be obvious that by the present method of forming the string and of cutting the filler from the same, those tobacco portions which each are intended to form a string, may vary within certain limits, without this having any influence on the quantity of tobacco in the bunch filler stamped out of the strings.

It is previously known to make fillers for cigar bunches by first forming a band of tobacco wherein the leaves lie in parallel to the transversal direction of the band, the latter having a width corresponding approximately to the length of the bunch, this band being then cut even at the edges, the ends of a plurality of leaves being then cut off, of course, whereupon filler blanks (strings) are being successively cut to the desired width by transversal cuts, a third cut being then finally performed for the purpose of forming the filler to the shape of the cigar. This method, however, does not bring about the purpose of the present method at all, inasmuch as the waste, which will be comparatively abundant, consists of tobacco portions that may only be used for an inferior tobacco product. Besides, these strings cut out of tobacco bands are not comparable with the strings produced according to the present invention, inasmuch as the former possess cut lateral faces, where-

as the latter have no cut surfaces prior to the stamping of the bunch filler, in that everyone of them is produced out of a portion of tobacco leaves or leaf parts which have only 5 been subjected to pressing in the transversal direction of the leaves on having been arranged in parallel to each other.

The stamping should be effected by means of a stamp cooperating with a die-block, that 10 is to say, the stamp is to be pressed against the whole upper surface of the portion to be stamped out of the string, so that the said portion is moved down through the hole of the die-block.

15 A machine according to the invention is illustrated in the accompanying drawings, where Fig. 1 is a vertical longitudinal section, Fig. 2 a vertical transversal section, and Fig. 3 a plan view of the machine. Fig. 20 4 represents a diagrammatical representation of the string, such as it appears after the filler required for the cigar bunch has been stamped out and removed.

25 2 designates the container for the filler tobacco mounted on the frame 1. From this container, the tobacco is transferred, either by hand or by means of a suitable mechanical device, to the feeding-in channel 3. From this feeding-in channel 3, the tobacco 30 falls down into a horizontal pressing channel 5, 6 when a door 4 secured on a rotatable shaft 22 and provided between the two channels occupies the open position shown with chain-dotted lines in Fig. 1. The pressing 35 channel is formed by a plate 5 and by upwardly directed walls 6 connected to the lateral edges of said plate. Entering the rear end of the pressing channel is a piston 25 consisting of a bent plate, said piston being attached to a piston rod 30 adapted to be moved to and fro in the horizontal direction.

The fore end of the pressing channel 5, 6 is 40 closed by a head wall 9 of sheet metal. Thus the tobacco leaves introduced into the 45 pressing channel will be pressed together between the said head wall 9 and the piston 25 when the latter is advanced.

The bottom of the fore end of the pressing 50 channel 5 consists of a die-block 24 for the stamp 10 which is adapted to be moved up and down and which serves to stamp out the bunch filler out of the filler tobacco, which latter is pressed together in the front part 55 of the pressing channel in the manner disclosed more fully hereinbelow.

The pressing surface of the stamp is whole 60 and has the same outline as the desired bunch filler, so that the whole upper surface of that portion of the string which is to be stamped out is subjected to the pressure of the stamp, and is pressed down through the die-block 24, the hole of which is of such a shape as to fit accurately to the stamp.

65 The pressing channel 5, 6, including the

feeding-in channel 3, the head wall 9, a wall 31 forming the roof of the upper portion of the pressing channel and connected to the front head wall 9 of the feeding-in channel 3, is supported by the bracket 19 mounted 70 on the frame 1, while the piston rod 30 is carried by and movable in guides 33 in another bracket 34 provided on the frame 1.

The tobacco leaves are introduced into the 75 pressing channel in such a manner that their longitudinal direction will coincide, approximately at least, with the transversal direction of the pressing channel.

Before the piston 25 commences to move 80 forwards from the position shown with full lines in Fig. 1, the door 4 moves into the closed position.

The stamp 10 then occupies the upper position shown in Fig. 1, that is to say, engages 85 the opening provided therefor in the upper wall 31 of the front part of the pressing channel.

The forward movement of the piston is 90 interrupted at certain intervals, and these interruptions are followed by short return movements of the piston. By this means the tobacco leaves will be successively arranged in such a manner as to be caused to lie in parallel to the piston 25, that is to 95 say, to the transversal direction of the pressing channel.

When the piston 25 has reached its foremost position indicated with chain-dotted lines in Fig. 1, the filler tobacco having thus 100 been formed into a string between the piston and the head-wall 9, the stamp moves down through the pressing channel and the die-block 24, thus stamping out a bunch filler to the exact cross-sectional shape of the stamp.

105 The stamped out bunch filler falls down into a container, or directly into the machine where it is to be worked further.

110 After the stamping operation has been completed, the stamp and the piston will move into their initial positions.

According to the embodiment described and shown, the pressed string is about twice as long as the cross sectional surface (the stamp surface) of the stamp, and stamping of the bunch filler is effected out of the middle portion of the string and in such a manner that the longitudinal direction of the bunch coincides with that of the string. Furthermore, the widest portion of the stamp surface, is of the same width as that of the string, so that the remainder of the string (the waste) will be divided into two parts by the stamping of the bunch filler, which parts are of a comparatively great 120 length. These waste portions, which are designated by *a* and *b* in Fig. 4, and which, as will be readily understood, are constituted by long leaves or long leaf parts, are removed either by hand or by a suitable me- 125 130

chanical means, and in the pressing channel they are brought together with tobacco leaves fetched out of the container 2, in order to form another string together with 5 said tobacco leaves.

The stamp 10 is secured on a cross piece 20 provided above the front part of the pressing channel, said cross piece 20 being in turn attached to the upper ends of two vertical slide rods 11, for which guide sleeves 35, 36, 37 are provided on the bracket 19 and the upper and lower parts respectively of the frame 1 (Figs. 1 and 2).

Moreover, a horizontal shaft 14 is rotatably mounted in projections 38 of the frame, said shaft 14 having secured thereon the one ends of two arms 12 engaging with their other forked ends each about one of the slide rods 11 and between stop rings or 20 flanges 13 provided on said rods.

An arm 15 is also secured on the shaft 14, said arm being provided with a roller 39 engaging a cam slot in a cam disk 16 attached to the main shaft 17 mounted in 25 the frame 1, said main shaft being driven, for instance, by means of a belt transmission from a suitable source of power.

Furthermore, an arm 21 is secured on the shaft 22 to which the door 4 is attached, 30 said arm 21 engaging by means of an elongated slot 40 a pin 41 on an arm 23 attached to the cross piece 20. When the piston 25 has reached its foremost position in the pressing channel, the stamp 10 moves downwards, that is to say, performs its working 35 stroke, through the medium of the parts 16, 39, 15, 14, 12, 13, 11, 20, at the rotation of the main shaft 17, the door 4 being then turned upwards and opened by means of 40 the parts 21, 22, 23. The piston then returns into the initial position, so that another set of tobacco leaves may be introduced into the channel.

The piston rod 30 is pivoted at its rear 45 end to the one arm of a double armed lever 7 which is rotatably mounted on the shaft 14, the other arm of said lever being provided with a roller 42 engaging a cam slot in a cam disk 8 attached to the main shaft 50 17.

Through the last mentioned arrangement, the piston is caused at the rotation of the main shaft to move to and fro in the pressing channel in the proper relation to the 55 movements of the stamp and the door.

What I claim is:—

1. A machine for making cigar fillers, comprising a press mold having a horizontal channel formed therein, the width of which 60 is equal to the length of the desired strings, a plunger mounted above the one end of said press mold, a head wall closing the end of the channel adjacent the plunger, a piston movable in the channel toward the head wall to press the filler material between it

and said head wall, a door at the top of said channel, said door engaging the upper side of the piston to retain the door in its closed position during the working stroke of the piston, and means whereby the working 70 stroke of said piston is interrupted at predetermined intervals and whereby the piston makes short return movements on said interruptions.

2. A machine for making cigar fillers comprising a press mold having a horizontal channel for receiving a portion of tobacco, a transversal wall at one end of the channel, a die in the bottom of said channel near the wall, said die having an opening which is of the same size and form as the filler, a top wall for the said channel end, said top wall having an opening opposite the die-opening, a plunger mounted to enter through the said opening in the top wall 75 and adapted to cooperate with the die to cut out the filler from the tobacco portion and move it from the channel through said die-opening, a piston adapted to be moved in the channel toward said end wall to press 80 the tobacco portion between it and said wall, a door disposed at the top of the channel, said door joining the upper side of the piston when in its closed position, in which the door must be kept when the piston performs its working stroke, and means whereby the working stroke of said piston is interrupted at predetermined intervals, whereby the piston makes short return movements 85 on said interruptions.

In testimony whereof I affix my signature.
